UNITED STATES PATENT OFFICE.

CARL D. BROWN, OF HOPEDALE, MASSACHUSETTS, ASSIGNOR TO DRAPER CORPORATION, OF HOPEDALE, MASSACHUSETTS, A CORPORATION OF MAINE.

WARP STOP MECHANISM FOR LOOMS.

Application filed October 11, 1923. Serial No. 668,011.

To all whom it may concern:

Be it known that I, CARL D. BROWN, a citizen of the United States, and a resident of Hopedale, in the county of Worcester and 5 State of Massachusetts, have invented an Improvement in Warp Stop Mechanisms for Looms, of which the following description, in connection with the accompanying drawings, is a specification, like characters 10 on the drawings representing like parts.

This invention relates to warp stop mechanisms for looms whereby on the occurrence of a fault in the warp the loom may be stopped.

15 Warp stop mechanisms now ordinarily in practical use are located between the warp beam and harnesses, and in cases where the main portions of the warp stop mechanism are positioned below the plane of the warp 20 threads it frequently becomes necessary to move the warp beam back out of interfering relation with the warp stop mechanism or limit the size of the mass of warp wound upon the warp beam, and in such type of 25 warp stop mechanism, an objectionable amount of lint is liable to accumulate on parts of the warp stop mechanism below the warp threads.

It frequently happens during weaving 30 that as the warp threads pass from the warp beam frontwardly, a snarl may occur in the warp, or two adjacent warp threads may become stuck together by the sizing used in finishing the yarn, or in some cases one of 35 the warp threads may contain an objectionable bunch or snarl in its length, which if woven into the cloth would make a defect.

One of the objects of the present invention, therefore, is to provide a warp stop 40 mechanism of such a character and construction that it will not necessitate that the warp beam be moved back, and at the same time permit the warp beam to be supplied with the normal or full amount of warp.

45 Another important feature of the invention consists in so called "drop wires" being constructed and arranged not only to effect loom stoppage should a warp thread break or become too slack for weaving purposes, 50 but also in case a snarl occurs in a warp

thread or two of such warp threads be stuck together.

In accordance with the present invention, the drop wires when supported in normal weaving condition by unbroken warp 55 threads are below the feeler, and the feeler has a detecting movement above the drop wires.

The various features of the present invention and new combination of parts will 60 best be made clear from the following description and the accompanying drawings of one good practical form thereof, the true scope of the invention being definitely described by the claims. 65

In the drawings:

Fig. 1 is a sectional side elevation of a loom provided with the present invention;

Fig. 2 is a perspective view showing the main features of the invention on an enlarged scale and the feeler removed from its operative position; 70

Fig. 3 is a sectional side elevation showing by full lines the relation of parts during normal weaving operation, and by dotted lines one of the drop wires as having been moved into its operative position, with its end projecting upwardly into the path of feeler movement; 75

Fig. 4 is an enlarged perspective view 80 showing more particularly the drop wires and the various conditions that may occur in the warp threads during weaving.

The term "drop wire" is now usually employed for designating that part of the warp 85 stop mechanism which is supported by the warp threads during weaving and is herein used in its broad sense to include any form of such drop wire that will function as hereinafter described. 90

The loom frame 1 may be of any usual construction and have associated therewith a stop mechanism for effecting loom stoppage should a fault occur in the warp threads. As herein shown, the shipper 2 is 95 pivotally mounted at 3 on a bracket 4 secured to the loom frame and is connected with the train of stopping mechanism as usual, the construction being such that when the shipper is detached from its holding 100

notch, as usual in loom constructions, the loom will be stopped.

Pivots mounted on the loom frame at 5 is an arm 6 the end 7 of which normally bears upon the shipper when the latter is in its holding notch and the loom is in running condition. Connected to the arm 6 is a rod 8 pivotally associated at 9 with an arm 10 which is itself pivotally supported at 11 on a fixed part of the loom. Pivotally supported on the fulcrum 9 is a dog 12 adapted to be raised and lowered into and from the path of a bunter 13 carried by the lay. In the present instance the dog 12 is controlled 15 in its movements from the warp stop mechanism through a rod 14 connected at 15 to a dog controller 16, in a manner substantially the same as that described in the patent to Edward S. Stimpson, No. 1,409,428, dated 20 March 14, 1922, the construction being such that should the dog 12 remain in the path of the bunter 13 on the backward movement of the lay the shipper will be dislodged from its holding notch and the loom be stopped.

25 At each side of the loom frame is a bracket or support 17, Fig. 2, to which is adjustably secured the frame 18 extending transversely of the loom. The frame 18 is shown as provided with side projecting lugs 19 having 30 slots 20 through which pass the adjusting and securing bolts 21, so that the frame 18 may be properly secured in place and in the desired adjusting position.

Extending between the side members of the frame 18 are the warp rests or supports 22 and intermediate the supports 22 the drop wires are located.

The drop wires are of novel construction and shown as of plate form, and the drop wires are supported for rocking movement upon drop wire supports. Such supports are constituted as bars 23 extending between the side members of the frame 18 transversely of the loom and each held in a bearing 24 on each of the side frames. Two rows of drop wires are shown in the present instance, but it will be understood that the invention is not restricted to this number of rows of drop wires because any number of rows may 50 be employed.

The drop wires 25 are shown as of the plate form and each is provided with openings 26—27, one at each side of the drop wire support 23 for engagement respectively with 55 two adjacent warp threads *a*. One of the two adjacent warp threads passes through the opening 26 of the drop wire and then over the top of the drop wire support 23, while the other of the two adjacent warp threads passes over the drop wire support 23 and 60 through the other opening 27 of the drop wire, the construction and arrangement being such that when the warp threads are in normal working condition, the drop wires 65 25 will be held in an inoperative position rel-

ative to the feeler, to be described. Each of the drop wires 25 is slightly over-balanced at one end, so that should both of the warp threads associated with the drop wire to maintain it in its inoperative position, become broken, and the drop wire thus be freed from warp thread control, the lighter end of the drop wire will be projected upwardly into the path of feeler movement. In the present instance the drop wires are over-weighted at that end containing the opening 27, which is the front end of the drop wires, and should both warp threads which contribute to the support of the drop wire in its operative position, become broken or too slack, the rear end portion, that containing the opening 26, in the present instance, will be projected upwardly into the path of feeler movement and effect loom stoppage, as will hereinafter more fully appear.

It happens at times that the adjacent warp threads may be snarled together, or a bunch of lint may so join the warp threads as to eventually cause breakage of one or both of them as the warp threads move towards the front of the loom during weaving operation. An important feature of the invention therefore consists in providing each drop wire with a snarl detector which will detect the presence of a snarl in the warp threads and on the occurrence thereof cause the drop wire to be moved into its operative position to effect loom stoppage. The snarl preventer in the present instance is formed by the rear edge portion of each drop wire which is inclined with respect to the plane of the warp threads, such that should a snarl occur it will engage the inclined rear edge of the drop wire, and as the warp threads move frontwardly during weaving, force the rear end of the drop wire upwardly into the path of feeler movement and effect loom stoppage. As shown, the rear end 28 of each drop wire has its rear edge portion 29 inclined upwardly such that should a snarl, as *b*, Fig. 4, meet the upwardly inclined edge 29 of a drop wire as the warp threads move frontwardly, the snarl will cause the rear end 28 of the drop wire engaged by it to be projected upwardly into the path of the feeler.

The feeler has a detecting movement which is wholly above the drop wires when the latter are maintained in their normal position during weaving by properly conditioned warp threads, and the feeler is likewise positioned above the warp threads. In the present instance the feeler is shown as comprising the side members 30, one of which is indicated in Fig. 2, and between the side members extend the bars 31, the lower edge portions of which are turned downwardly, as indicated at 32, Fig. 3, the lower edge of the downturned portion 32 being normally above the warp threads and

above the drop wires, but adapted to engage one or the other end of the drop wire should such end be projected or raised into the path of feeler movement.

5 The feeler is given its detecting movement through a train of mechanism which may be substantially the same as that shown and described in the Stimpson Patent, No. 1,409,428, March 14, 1922. As shown, the 10 side members 30 of the feeler have upwardly projecting arms 33 through which extends the rod 34, the end projecting portions 35 of which are adapted to rest in the open sockets 36 of the arms 37 projecting upwardly from the feeler rock shaft 38 which may be conveniently supported in bearings formed in the side members of the frame 18.

Extending from the feeler rock shaft 38 is an arm 39 having an elongated socket 40, and extending upwardly through the arm 39 is an actuator 41 which extends downwardly and is pivotally connected at 42 to a cam follower 43 normally held in cooperative relation with the cam 44 mounted on 25 the shaft 45 at the lower end of the loom frame. A spring 46 serves to maintain the follower 43 normally in contact with the cam but permits it to yield. Between a collar 47 on the actuator 41 and the under surface of the arm 39 is interposed the spring 48, the construction being such that the feeler may be arrested in its feeling movement in either direction substantially as set forth in the Stimpson patent, hereinbefore 30 referred to.

Secured to the feeler rock shaft 38 is the arm 49 to which is connected the rod 14 hereinbefore described as associated with the dog 12 for moving it into and out of the path 35 of the bunter 13.

The warp threads *a* are, as usual, wound upon the warp beam 50, Fig. 1, and pass over the usual guide or roller 51 and thence forward through the warp stop mechanism 45 to the harnesses or shedding mechanism. As hereinbefore noted, two adjacent warp threads are associated with each drop wire, one of the warp threads being passed through the opening 26 in the drop wire at 50 one side of the drop wire support 23, then over said support towards the front of the loom, and the other of the adjacent warp threads being passed over the support 23 and through the opening 27 of the drop 55 wire, the effect being that the two adjacent warp threads when in normal weaving condition, maintain the drop wires in normal position, as indicated in Figs. 1 and 2, and wholly below the path of movement of the 60 feeler. Should the warp thread which passes through the opening 26 of the drop wire break, the tension exerted by the other warp thread passing through the opening 27 of the drop wire will cause the front end 65 portion of the drop wire to be raised into the

path of movement of the feeler and arrest the feeler in its detecting movement, and thus position the dog 12 for engagement by the bunter 13 on the lay, to effect loom stoppage, as hereinbefore described. This condition is shown by the position of the drop wire at A, Fig. 4.

Should, however, the warp thread which passes through the opening 27 of the drop wire, break or become too slack, the tension 70 of the adjacent thread passing through the opening 26 of the drop wire will cause the rear end portion 28 of the drop wire to be raised into the path of movement of the feeler and effect loom stoppage. This condition is shown by the feeler at B, Fig. 4.

Should both of the two adjacent warp threads which normally maintain the drop wire in its inoperative position, become broken, as indicated at C, Fig. 4, the over-weighted front end of the drop wire will cause the rear end 28 thereof to be projected upwardly into the path of feeler movement and effect loom stoppage.

Should a snarl, such as *b* occur in the 90 warp threads, or such threads be stuck together as they move towards the front of the loom during weaving, the snarl or stuck together portions of the two threads will meet the inclined surface 29 of the drop wire, as indicated at D, Fig. 4, and raise the end 28 of the drop wire into the path of movement of the feeler and effect loom stoppage. Thus the loom will be stopped should any one of the warp threads break, or should two adjacent warp threads break, or should a snarl 95 occur in the warp threads as they move towards the front of the loom.

It may sometimes happen, owing to the 100 number of warp threads in the loom, that one or more of the drop wires may be associated with a single warp thread. In this case, as indicated at E, Fig. 4, the single warp thread will be passed through the rear opening 26 of the drop wire, then over 105 the top of the drop wire support 23, and then through the front opening 27 of the drop wire, and should this warp thread break, the over-weighted front end of the drop wire containing the opening 27 will cause the rear end 28 to be projected upwardly into the path of feeler movement and effect loom stoppage.

As shown in the present instance of the 110 invention, the drop wire supports 23 are of circular form in cross-section, and each of the drop wires is provided with an opening through which the drop wire support may extend. To facilitate the application of the drop wires to the drop wire support, each 115 of the drop wires may be provided with a slot 52, Fig. 4, at E, of less dimension than the drop wire support 23, and the finger portions 53, constituting the side walls of the slot, are in such case made as spring 120 125 130

15 fingers which may be deflected laterally to a sufficient extent to permit the drop wire to be applied to the drop wire support in a direction transversely of the axis of the drop
 5 wire support, so that when the drop wires are finally placed upon the drop wire supports, they may be maintained in proper relation thereto. This construction obviates the necessity of stringing the drop wires
 10 upon the drop wire supports by longitudinal movement of the drop wire supports through the opening in the drop wires.

The feeler may be variously contrived, but the form as hereinbefore described is found to be a good practical embodiment of this feature of the warp stop motion, and when such form is used, the side members 30 of the feeler are preferably provided with guideways 54 into which may extend the 20 flanges 55 projecting upwardly from the side members of the frame 18, as indicated in Fig. 2.

From the construction described it will be noted that the main portions of the warp 25 stop mechanism may be interposed between the warp beam and harnesses without necessitating any modification either in the size of the warp beam or its economical position with respect to floor space, and that none of 30 the parts of the main warp stop mechanism is located below the plane of the warp threads, the warp supports 22 themselves being susceptible of being formed shallow and of a construction which will not interfere 35 with any of the parts beneath. Any lint that may be formed during the passage of the warp threads during weaving will have free and unobstructed exit without accumulation upon any parts of the warp stop mechanism.

40 While the train of mechanism for knocking off the shipper is herein shown and described as of the same general type as that in the Stimpson patent, hereinbefore mentioned, and is effected by a bunter 13 associated with the lay 56, the present invention is more particularly directed to the main parts of the warp stop mechanism, and any 45 train of mechanism for effecting loom stoppage through the warp stop mechanism may be employed.

The warp supports 22 are arranged with 50 relation to the drop wires, so that when a drop wire has one end projected upwardly, the other end may come in contact with the adjacent warp support which will act as a stop for determining the position of the raised end of a drop wire, as indicated by dotted lines, Fig. 3, and full lines, Fig. 4.

60 What is claimed is:

1. In a warp stop mechanism for looms, the combination of a drop wire support extending transversely of the loom, a drop wire pivotally hung upon the support for rocking movement and adapted to be main-

tained in a normal inoperative position by a warp thread during weaving and to pivot upon the support and raise one or the other end of the drop wire into an operative position should the associated warp thread be 70 broken or become too slack, a feeler having a detecting movement longitudinally of and above the plane of the warp threads and drop wires and adapted to engage the raised end of a drop wire and be arrested thereby 75 when the warp thread becomes broken or too slack, and means for stopping the loom when the feeler is arrested by the raised end of a drop wire.

2. In a warp stop mechanism for looms, 80 the combination of a drop wire support extending transversely of the loom, a series of drop wires pivotally hung upon the support for rocking movement and each adapted to engage a warp thread at one side of 85 the support and another warp thread at the opposite side of said support during weaving that both ends of the drop wire may be held in inoperative position, a feeler having a detecting movement longitudinally of and above the plane of the warp 90 threads and drop wires and adapted to be arrested by a drop wire when one end thereof is raised into the path of the feeler by abnormal condition of one of the warp 95 threads, and means for stopping the loom when the feeler is arrested by the raised end of one of the drop wires.

3. In a warp stop mechanism for looms, 100 the combination of a series of drop wires each sustained in an inoperative position by the joint action of two warp threads and having a snarl detecting portion by which a drop wire may be moved into its operative position by frontward movement of 105 the intact warp threads in case two warp threads become snarled or stuck together, a feeler having a detecting movement, and means for stopping the loom should a drop wire assume its operative position due 110 either to a snarl in the intact warp threads or by breakage or abnormal slackness in one of the warp threads.

4. In a warp stop motion for looms, the combination of a feeler having a detecting movement above the plane of the warp threads, a series of drop wires mounted for rocking movement and each sustained in its inoperative position by two adjacent warp threads, and each drop wire having an inclined end portion facing towards the rear of the loom and constituting a snarl detector portion adapted to effect movement of a drop wire about its fulcrum into operative position through engagement by a 120 snarl in two adjacent warp threads as they move towards the front of the loom, and means for stopping the loom when the feeler is arrested by a drop wire.

5. In a warp stop mechanism for looms, 125

- the combination of a series of drop wires loosely mounted for rocking movement to permit either end to be raised into operative position and each sustained in its inoperative position by two adjacent warp threads, a feeler having a detecting movement longitudinally of and above the plane of the warp threads, and means for stopping the loom when the feeler is arrested in its detecting movement by either raised end of a drop wire projecting into the path of the feeler. 5 70
6. In a warp stop mechanism for looms, the combination of a feeler having a detecting movement longitudinally of and above the plane of the warp threads, a series of drop wires which are wholly below the feeler when supported by normally conditioned warp threads during weaving 10 75
- 20 and pivotally supported between their ends that one or the other end may be moved upwardly into the plane of movement of the feeler when a warp thread breaks or becomes too slack, and means for effecting loom stoppage when the feeler is arrested by a raised drop wire. 25 80
7. In a warp stop mechanism for looms, the combination of a feeler having a detecting movement above the plane of the warp threads, a series of drop wires, each 30 having a warp-snarl detecting portion, by which a drop wire may be moved into operative position by the intact warp threads as they move towards the front of the loom, and means for stopping the loom should either a snarl or breakage occur in the warp threads and a drop wire be raised into the path of movement of the feeler. 35 85
8. A drop wire for warp stop mechanisms for looms, comprising a plate having an opening between its ends for a drop wire support and a slot leading from the edge of the plate into the opening, and spring fingers for partially closing the slot but adapted to permit the drop wires to be placed upon the support transversely of its length. 40 90
- 50 95
5. A drop wire for loom warp stop mechanisms, comprising a plate having an opening for a drop wire support and a snarl detecting edge facing the rear of the loom when the drop wire is mounted upon the support and adapted to cause the drop wire to be moved about its support by a snarl in the unbroken or intact warp threads as they move towards the front of the loom. 55 100
10. In a warp stop mechanism for looms, the combination of a drop wire support extending transversely of the loom, a series of drop wires of plate form overweighted at one end and mounted for rocking movement upon the support and each having an opening for the passage of a warp thread at each side of and below the support, and a feeler having a detecting movement above the drop wires when they are normally supported by the warp threads during weaving and adapted to be arrested by the raised end of a drop wire on the occurrence of an abnormal condition in the warp threads. 60 105
11. In a warp stop mechanism for looms, the combination of a series of drop wires having a warp engaging recess in each end, a support on which the drop wires are pivotally mounted for movement of either end of a drop wire upwardly into operative position should one of two engaged warp threads break or become too slack, a feeler having a reciprocatory movement above the plane of the warp threads and adapted to be arrested by either end of a drop wire, and means for stopping the loom when the feeler is arrested. 65 110
12. In a warp stop mechanism for looms, the combination of a drop wire support, a series of drop wires pivotally mounted on said support and having a warp thread engaging eye at either side of said support by which the drop wires may be held in inoperative position by two warp threads passing over said support and each engaged with one of said eyes, a feeler having a detecting movement above the warp threads and adapted to be arrested when either end of a drop wire is raised, and means for stopping the loom when the feeler is arrested. 70 115
13. In a warp stop mechanism for looms, the combination of a feeler having a detecting movement, means for stopping the loom when the feeler movement is arrested, a series of drop wires normally supported in an inoperative position during weaving, each constructed and arranged to be moved to operative position to arrest the feeler should one or both warp threads engaged thereby become broken or too slack and also to be moved into operative position by longitudinal movement of intact warp threads which are snarled or struck together. 75 120
14. In a warp stop mechanism for looms, the combination of a feeler having a detecting movement, means for stopping the loom when the feeler movement is arrested, a series of drop wires normally supported in an inoperative position by the warp threads during weaving, and having a warp snarl detecting portion by which a drop wire may be moved into operative position to arrest the feeler and effect loom stoppage by longitudinal movement of the intact warp threads. 80 125
15. In a warp stop mechanism for looms, the combination of a drop wire support extending transversely of the loom, a series of drop wires mounted for rocking movement upon the support and each having a warp thread engaging portion at opposite 85 130

sides of the drop wire support, one end portion of a drop wire being heavier than the other so that a drop wire may be moved into operative position by rocking movement upon its support due to the tension of the intact warp thread when the companion warp thread breaks or becomes too slack and will act by gravity to move to

operative position upon its support when both warp threads break, and a feeler having a detecting movement and adapted to be arrested by an operatively positioned drop wire.

In testimony whereof, I have signed my name to this specification.

CARL D. BROWN.
